UNITED STATES PATENT OFFICE.

JOHN A. ISLIN, OF NEWPORT NEWS, VIRGINIA.

RIDDLE.

1,030,241.

Specification of Letters Patent. Patented June 18, 1912.

Application filed November 25, 1911. Serial No. 662,432.

To all whom it may concern:

Be it known that I, JOHN A. ISLIN, a citizen of the United States, residing at Newport News, in the county of Warwick and 5 State of Virginia, have invented certain new and useful Improvements in Riddles, of which the following is a specification.

The riddle which is the subject of the present invention is designed more particularly for use in foundries, and it is the object of the invention to provide an improved structure whereby the wire screen may be readily removed from the body of the riddle, in order that it may be renewed when worn, 15 or changed for one of different mesh.

In order that the invention may be better understood, reference is had to the accompany drawing in which—

Figure 1 is a plan view of the riddle. 20 Fig. 2 is a cross-section on the line 2—2 of Fig. 1. Fig. 3 is a plan view of a modified form of riddle. Fig. 4 is a cross-section on the line 4—4 of Fig. 3.

Referring specifically to the drawing, 25 denotes the body of the riddle, the same being cylindrical in form, as usual. The body may be a plain annular sheet metal band having a rolled rim at the top, in which a stiffening wire 11 is embedded. At the bottom of the band is an upward and inward bend 12, which forms a shoulder on which the wire mat or screen 13 seats, the same comprising a ring over which the screening material is crimped or otherwise fastened. 30 The diameter of the mat is such that it fits snugly within the body 10.

In order to hold the mat 13 in place, 35 spring latches are provided. These latches are strips 14 of spring metal which are riveted or otherwise fastened at one of their ends to the band 10, on the outside, and near the top thereof, and have at their other ends lateral bends 15 which extend inwardly through apertures 16 in the band so as to

engage the top of the marginal portion of 45 the mat, said mat being thus securely held in place within the band between the bottom shoulder and the inturned ends of the latches. To release the mat, it is necessary only to spring the latches outward, after which the 50 mat may be readily removed in order that it may be renewed when worn, or changed for one of different mesh. Instead of making the body of the riddle out of a sheet metal band, the band may be a wooden one. 55

In the modified structure shown in Figs. 3 and 4, the body of the riddle is a wooden rim 17 which is reinforced by sheet metal bands 18 which are wrapped around the same longitudinally, so as to extend over the 60 top and bottom edges and the inside and outside of the rim. On the inside of the rim, near the bottom thereof, the bands have outstanding bends 19 forming shoulders on which the mat 13 seats. The bands are secured to the rim by rivets, certain of which latter, a short distance above the bends 19 have heads 20 which serve to hold the mat in place on the shoulders formed by the 65 bends. 70

The mat employed with the last described structure can also be readily removed, as there is enough spring in the wooden rim 17 to allow the mat to pass the rivet heads 20. 75

I claim:

A riddle comprising an annular band, reinforcing bands passing around the same endwise, and having internal shoulders, a screen removably supported on the shoulders, and screen retaining-means on the reinforcing bands. 80

In testimony whereof I affix my signature in presence of two witnesses.

JOHN A. ISLIN.
